UNITED STATES PATENT OFFICE.

SAMUEL BUYER, OF YONKERS, NEW YORK.

LOOP FOR HOSE-SUPPORTERS.

1,076,265.

Specification of Letters Patent.

Patented Oct. 21, 1913.

Application filed April 17, 1912. Serial No. 691,540.

To all whom it may concern:

Be it known that I, SAMUEL BUYER, a citizen of the United States of America, residing at Yonkers, Westchester county, and State of New York, have invented certain new and useful Improvements in Loops for Hose-Supporters, of which the following is a full, clear, and exact description.

This invention relates to improvements in hose-supporter loops of the expandable type, out more especially to the lower or clamping end thereof which is adapted to receive and hold the button upon the other element of the supporter.

15 My special features of improvement will be hereinafter more fully described and finally pointed out in the appended claims; reference being had to the accompanying drawing, forming part hereof, wherein—

20 Figure 1 is an enlarged face view of a hose-supporter embodying my invention, the lower part being shown in section; Fig. 2 is an enlarged vertical sectional detail view of the lower or clamping end of the loop;

25 Fig. 3 is a vertical sectional view, the section being taken on a line 3—3 in Fig. 2; Fig. 4 is a sectional end view, the section being taken on a line 4—4 in Fig. 2; and Fig. 5 is a sectional view taken on a line 5—5

30 in Fig. 2, the ends of the legs being of modified form.

In the drawing, the numeral 1 indicates a hose-supporter loop of ordinary construction so far as the general outline is concerned, and which is provided with yieldable side-members 2 bent inwardly or toward each other at their lower or free ends. My invention pertains mainly to the shaping of the free ends of the said side-members 2 and

40 the arrangement of certain elements which coact with the free ends thereof to firmly grip the button on the other member of the hose-supporter, which is well known and which is not shown. One of the features of 45 my improvement is the curving or recessing of the said side-members 2, as at 3. The members or legs 3^a extend from the curved or recessed portion of the members 2 toward each other, as shown, and are preferably 50 flattened or widened at their free ends as at

4. The flattening of the ends of the legs 3^a enlarges them at their extremities for a purpose which I will now explain. Over the members or legs 3^a I place a metallic sleeve 5, which is contracted at its ends 55 as at 6, the area of the contracted ends of

the sleeve being slightly larger than the cross-sectional area of the rounded portion of the legs 3^a, but the diameter of the said contracted ends is less than the width of the 60 flattened or enlarged ends 4 of the legs 3^a. It will be evident that the sleeve 5 permits the members 2 of the loop to be spread apart, but prevents the said members, or rather the legs 3^a thereof, to be spread to an extent 65 which would carry the legs 3^a out of the sleeve at the ends thereof. The constricted ends of the sleeves provide stops against which the enlarged or flattened ends 4 of the legs 3^a will strike and thus prevent abnormal spreading of the side-members 2 when they are forced apart by the passage 70 of the button or head along the portions 9 of the side-members 2 or by reason of undue strain.

To prevent the metal sleeve or keeper 5 from contacting with the fabric of the hose, I cover the same with a sleeve of rubber or other cushioning material, the length thereof being slightly greater than that of 80 the metal sleeve 5 and extending into the recess 3 of the expandable side-members 2, whereby a comparatively large padding or cushion is provided for the button, the said recess also acting to keep the cushioning 85 sleeve 7 in position.

In Fig. 5 the ends of the legs 3^a are shown in form of rounded or ball-like enlargements, instead of the flattened or widened enlargements hereinabove described, the 90 loop in other respects being similar to that shown in the other views.

Having now described my invention, what I claim and desire to secure by Letters Patent is:

1. A hose-supporter loop having side members provided with inwardly turned legs at the clamping end of the loop, the extremities of said legs being flattened and broader than the diameter of said legs, and a metal sleeve surrounding said legs, the sleeve having a diametrically enlarged central portion and constricted ends, the flattened extremities of the legs normally lying within the said enlarged portion of the 105 sleeve and when spread apart, bearing against the constricted ends thereof.

2. A hose-supporter loop, comprising yieldably connected side-members turned inwardly at their free ends to form legs, the 110 extremities of said legs being flattened and broader than the diameter of said legs, a

2
metal sleeve surrounding said legs, the ends of said sleeve being slightly larger than the diameter of said legs but smaller than the flattened ends thereof, and a rubber sleeve or cushion carried by said metal sleeve and cushion being at the clamping end of the loop.

3. A hose-supporter loop comprising yieldably connected members turned inwardly at their free ends to form legs, said members being curved adjacent said legs to form recesses, the extremities of said legs being flattened and broader than the diameter of said legs, a metal sleeve surrounding

said legs, the ends of said sleeve being narrower than the flattened ends of said legs, and a rubber sleeve or cushion carried by said metal sleeve and extending into the recesses in the yieldable members of said loop, the said metal sleeve and cushion being at the clamping end of the loop.

Signed at New York city, N. Y., this 15th day of April, 1912.

SAMUEL BUYER.
